MECHANISM FOR FEEDING STRIP MATERIAL
Cornelius Graham Mayer, Chobham, and John Bertram Killow, Betchworth, England, assignors, by mesne assignments, to Radio Corporation of America, Princeton, N.J.

Filed June 13, 1958, Ser. No. 741,923
Claims priority, application Great Britain June 18, 1957
9 Claims. (Cl. 226—50)

This invention relates to mechanisms for feeding strip material in opposite directions, particularly for feeding film in cinematograph projectors.

It is often desirable to reverse the direction of film feed through a cinematograph projector; for example, when an initial length of film has been passed through the projector to ensure that the apparatus is functioning properly and it is desired to go back to the beginning of the film to begin the full length showing of the film. Moreover, where a sound track is being recorded on the edge of a picture film, it is sometimes necessary to feed the film backwards a little in order to bring the sound track into register with the picture film or for the purpose of erasing and re-recording.

Such reverse movements of the film have to take place through the normal projection gate between the driving sprockets, and are quite distinct from the reverse feeding which takes place outside the gate, after the full length has been shown, for locating the beginning of the film at the outer end of the coil so as to enable the film to be shown again.

The problem of reversing the film becomes difficult in the case of sound projectors because, while the film has to move in steps past the gate, it must move smoothly past the sound scanning device and is, therefore, arranged to pass over a drum associated with a flywheel. When reverse feed takes place, the film, instead of being drawn over the drum by a uniformly rotating sprocket may be drawn over the drum by means, such as claws, operating periodically on the film. Therefore, the maintenance of drum movement free from oscillations or jerks presents a problem which it is one of the main objects of the present invention to solve. Further objects of the invention are to ensure that the film, in the reverse movement, is kept taut between the sound drum and the sprocket by which it is delivered to the sound drum, and that no abnormal accumulations of film occur anywhere along its track between the spool from which it is drawn and the spool by which it is taken up.

According to the invention, mechanism for feeding strip material in opposite directions between reversible rotary members, includes a rotor assembly which has a substantial inertial resistance to acceleration and comprises a drum or other rotor over which the strip passes in travelling between the rotary members, the rotor assembly being arranged to be rotated freely by the strip material travelling thereover in one direction, so as to smooth out fluctuations in the strip movement, and means other than the strip for driving the rotor assembly in the reverse direction at a speed such as to maintain tension in the strip between the rotor and one of the rotary members. It is advantageous to construct the rotor assembly so that it is not a simple flywheel but to construct it as a rotor with a separate flywheel. In the case of a cinematograph projector, as aforesaid, the rotary members are the sprockets and the drum or other rotor is the sound drum. Preferably the drum is arranged to drive the film by friction and friction means are provided for driving the rotor assembly in the reverse direction. The friction drive may comprise an intermediate rubber rimmed wheel movable to and from a position in which it is frictionally driven by a driving wheel and frictionally

2

drives the rotor assembly. The diameters of the engaging surfaces of the driving wheel, intermediate wheel, and rotor assembly may be such as to provide a double step-up gearing. Very conveniently the intermediate wheel is rotatably mounted on a slide arranged to be held in the driving position by a spring and positively moved away from such position, as well as permitted to move towards such position, by a manually actuated snap-action mechanism.

Advantageously, the circumferential speed of the drum is slightly higher than the speed of the film, during the reverse feed, so as to maintain tension continuously between the drum and the sprocket by which the film is delivered to the drum, in spite of fluctuating action due to claws or other means, such as an intermittently rotating sprocket. The dimensions of the apparatus are such that the diameter of the sound drum must be quite small and it is therefore desirable to provide, as suggested above, a separate flywheel, but this may be fixed coaxially to the drum.

It has been found desirable to employ a pressure roller to act on the film passing over the sound drum and it is necessary to provide guides for the control of the film path laterally in passing forward over the drum in order that the sound track on the film may be accurately aligned with respect to means provided for scanning such sound track. In order that the film may feed backwards round the sound drum, all such guidance on what then becomes the output side of the pressure roller has to be removed in order that stable film motion is obtained. It is desirable that the mechanical operation of removing such guides is carried out by the same snap action mechanism which causes the friction drive to be alternately engaged and disengaged from the drum assembly.

It frequently happens that the film to be fed through the mechanism has been cut and re-joined by means of a lap joint, or splice, whereby the thicknesses of the film is temporarily increased. For normal operation of the mechanism, such splices present no problem as the film is drawn forward around the sound drum by the action of the lower sprocket, and the pressure roller lifts momentarily to allow the splice to pass beneath it.

For reverse operation, however, the sound drum frictionally drives the film, and when a splice is fed backwards round the drum, the drum surface driving the film would be required to provide such additional forces as are required to lift the pressure roller in order that the splice may pass beneath it. In practice it is found that such driving forces cannot conveniently be provided within the dimensions of cinematographs apparatus. The roller is, therefore, made from a hard material, such as nylon, with an annular channel, centrally disposed along the length of the roller, filled with a ring of resilient material such as rubber. The resilient ring is of greater diameter than the roller and therefore stands proud of it. The roller is associated with a spring which biases the roller downwards onto the drum and, under the action of this spring, the resilient ring tends to flatten.

When feeding forward around the drum, therefore, the edges of the film which normally carry the sound tracks are backed, where the film passes beneath the roller, by the solid material of the flanges at the ends of the roller, and in practice, this is an important condition in order to be able to secure satisfactory scanning and recording of certain types of sound track.

When feeding backwards, the splice becomes gripped by the resilient center of the roller, particularly by virtue of the fact that the resilient material has a substantial arc of contact with the drum because of the flattening referred to above. The resilient material therefore grips the splice before the splice reaches the pinch between the drum and the hard flanges of the roller, and the resilient

material thereby provides the additional traction required to lift the roller and allow the splice to pass beneath it.

Conveniently the apparatus is driven by a reversible electric motor acting through an endless flexible band, such as a belt, passing over driving and driven elements, such as pulleys. The weight of the motor may be used to keep the belt taut, the motor being mounted on a hinged platform. Spring means, acting on the platform, may be provided for adjusting the belt tension and means may be provided for locking the platform in a fixed position for transport.

In order that the invention may be clearly understood, apparatus in accordance therewith will now be described in some detail, purely by way of example, with reference to the drawings which accompany the present specification and in which:

FIGURE 1 is a rear elevation of an assembly of mechanism forming part of a cinematograph apparatus;

FIGURE 8 is a side elevation of part of the mechanism of FIGURES 1 to 3.

FIGURE 9 is a perspective exterior view of the apparatus of which the mechanism of FIGURES 1 to 8 forms a part;

FIGURE 10 is a front elevation of part of the apparatus of FIGURE 9;

FIGURE 11 is a side elevation of the part appearing in FIGURE 10, a small portion thereof being shown broken away to disclose the interior;

FIGURE 12 shows a portion of the mechanism appearing in FIGURES 2 and 4;

FIGURE 13 is an end view of a portion of the apparatus of FIGURE 9;

FIGURE 14 is a sectional side elevation of a detail appearing in FIGURE 13; and

FIGURE 15 is a front elevation of a further assembly of mechanism in the cinematograph apparatus.

In the normal operation of the apparatus, the film to be projected is drawn off an upper spool S1 (FIGURE 9) by a sprocket 1, the film passing between a guiding shoe 2 and the sprocket 1 (FIGURE 3) which holds the film on the sprocket 1, to the gate past which it is drawn in known fashion, by cam operated claws 2A (FIGURE 15) fixed to a plate 2B mounted to oscillate about an axis 2C and also to move at right angles to its own plane under the action of two cams so as to cause the claws 2A to follow a path in the form of a closed loop as required. The intermittently moving film then passes between guide flanges 3, 4 (FIGURES 3 and 6), located either side of a skid 4A, to the pinch between a sound drum or rotor 5 and a pressure roller 6, the guide flanges 3, 4 being, during the forward feed of the film raised above to the dotted line positions of FIGURES 3 and 6. They are lowered to the full line positions by means described below. The roller 6 is mounted on a spindle 6C on an arm 6D pivoted about a fixed axis 6E. A spring 6A, acting on the arm 6D (FIGURE 7), presses the roller 6 towards the sound drum 5. The roller 6 is of nylon and is formed with an annular channel holding a rubber ring 6B for the purpose set forth above. The sound drum 5 is fixed to a shaft 8 (FIGURE 5) mounted in bearings 9, 10, and carrying a heavy flywheel 11, the inertia of which is such that the angular velocity of the sound drum 5 cannot fluctuate at the frequency at which the film is fed by the claws or at

any other frequency arising in the machine, with the result that the fluctuating progress of the film is converted to smooth progress enabling the sound track to be scanned for the reproduction of the sound recorded thereon.

After leaving the sound drum 5, the film passes over a pulley 5A to a sprocket 12, driven at the same speed as the sprocket 1, the film being held on the sprocket by a guiding shoe 12A. The film, after passing a guiding roller 13, is taken up by a spool S2 driven through a slipping clutch, in known manner, by pulleys and a helical spring belt 12B. A similar take-up drive is provided for the upper spool and means are described below for controlling the spools according to the direction of rotation.

When it is desired to reverse the motion of the film through the machine, a lever 14 fixed to a spindle 15, rotatable about a fixed axis and carrying a plate 16, is turned to the full-line position of FIGURE 3 in which the plate 16 is located substantially as shown in FIGURES 2 and 12. The movement of this assembly, comprising the lever 14 and plate 16, has a light snap action to-and-fro between positions in which a pin 17 on the plate 16 engages either side of an open-mouthed slot 18 in a crank 16A. The plate 16 is held in each of these positions by a hairpin spring 19 anchored at its ends respectively to a fixed point and to a point on the plate 16, and arranged to pass over a dead-center position as the plate 16 passes from one of the said positions to the other. When the plate 16 is moved from the position in which the pin 17 engages one side of the slot 18 to the position in which it engages the other side of the same slot 18, the pin 17 on the plate 16 knocks the crank 16A, pivoted about a fixed axis 16B, over a dead-center position, determined by an arcuate spring 16C anchored between a fixed point and the crank 16A, to the position shown in FIGURES 2, 4 and 12. The crank 16A controls the reverse movement of the drum 5 and flywheel 11, the spools S1 and S2, as well as the position of the guide flanges 3, 4. The return movement of the crank 16A is effected by knocking this back over the dead-center position when the plate 16 and pin 17 are returned across the slot 18. The lost motion between the plate 16 and the crank 16A enables the movements of the plate 16 to take place sharply, even though the movement of the crank 16A may be temporarily arrested as a result of the delayed engagement of certain gears 48, 51 or 48A, 51 (described below) controlling the drive for the spools, such delay being due to teeth meeting end on. The leverage and impact exerted by the plate 16, moreover, assist in overcoming the comparatively strong reaction of the spring 16C, which exerts a substantially stronger moment than the spring 19 and provides a quick action. The movement of the crank 16A in the counter-clockwise direction is arrested by an adjustable stop 16E (FIGURES 2 and 12). When the plate 16 is in the position of FIGURES 2, 4 and 12 against a second adjustable stop 16D, a bell-crank lever 20 (FIGURES 2 and 4) pivoted about a fixed axis 21 and connected to the plate 16 by a link 22, permits a spring 23 to hold a reciprocable slide 24 in a position such that the sound drum 5 is positively driven in the reverse direction to that in which it is driven by the film during the normal projection operation. The speed of the drum in this reverse direction is about 4% greater than the speed in the normal direction so as to ensure that there is no bunching or accumulation of the film between the sprocket 12 and the sound drum 5, particularly when the reverse drive begins.

The slide 24 is formed with two slots 25, 26 enabling it to reciprocate on two pins 27, 28 and, when it is in the position of FIGURE 2, an intermediate rubber wheel 29, rotatably mounted on the slide 24, transmits the drive from the rim 30a of a wheel 30 to the flywheel 11. The drive is by friction and the rubber wheel 29 has two rims 31, 32 of different diameters that respec-

tively engage the wheel 30 and a rim 33 on the flywheel 11, the wheel 30 being controlled by means described below to rotate only during the reverse film feed. The diameters of the engaging rims is such that a double step-up gearing is provided. When the lever 14 is turned to the position corresponding to the normal direction of film movement so that the plate 16 knocks the crank 16A back over the dead-center position to the position in which it engages the stop 16E, the link 22 turns the bell crank lever 20 to a position such that a lug 34 on the bell crank 20 pushes on a lug 35 on the slide 24 and moves it, against the action of the spring 23, to a position in which the rubber wheel 29 is separated from the wheel 30 and the flywheel 11.

During the reverse movement of the film, the guide flanges 3, 4 are retracted to the positions shown by full lines in FIGURE 6. The reason for this is that it has been found that, with the guide flanges 3, 4 continuously in the raised positions, the passage of the film over the skid 4A is unsatisfactory. This skid 4A (see FIGURE 6), which is not rotatable although it has a certain amount of play about its axis, has a certain amount of lateral play against a stiff helical spring 37, together with the retractable guide flanges 3, 4, which can move with the skid 4A, either toward or away from the spring 37, under control of a nut 37A screwed onto a spindle passing through the flanges 3, 4, the skid 4A and the spring 37. The movement is for the purpose of adjusting the lateral position of the film path over the drums 5. By retracting the guide flanges 3, 4 to below the surface of the skid 4A as shown in FIGURES 3 and 6, the film is free to follow a path out of the pinch between drum 5 and roller 6 without any lateral restraint whatever. The way in which the retraction of the guide flanges 3, 4, is effected will now be described.

The bell crank lever 20 is connected by a link 38 to another bell crank 39 rotatable about a fixed axis 40.

The link 38 is coupled to the bell crank 39 by a nipple 38A which is pivoted to the bell crank 39 and is adjustable along the link 38 so as to provide an adjustment to the angular location of bell crank 39 relative to bell crank 20. An elongated slot 41 in the bell crank 39 engages a pin 42 projecting from the rear of a slide plate 43. From the lower end of the slide plate 43, a pin 44 engages the rear guide flange 3 and also, through a bushing 45, the front guide flange 4. Spring loading of the rear guide flange 3 against the skid 4A is obtained by the spring 37, and of guide flange 4 against the skid 4A by a spring washer 45A, interposed between the flange 4 and a nut 37B. Thus, the dimension between the faces of the guide flanges 3, 4 is automatically maintained equal to the length of the skid 4A, to thus provide accurate lateral guidance of the film around the sound drum 5 when the guide flanges are in their raised positions and when the film is fed in the forward direction for projection.

When the bell crank lever 20 is moved to the position corresponding to reverse film feed, a corresponding movement is transmitted to bell crank 39 by the link 38 and adjustable nipple 38A. The slot 41 therefore acts on the pin 42 to move the slide plate 43 downwards, which in turn retracts the guide flanges 3, 4 to the positions of FIGURES 3 and 6 (full lines) by causing movement of the pin 44 and bushing 45. Conversely, when the bell crank lever 20 is returned to a position corresponding to normal direction of film feed, the guide flanges 3, 4 are pushed upwards by pin 44 and bushing 45 so that they stand proud of skid 4A, and firmly spring loaded inwards towards each other, against the ends of the skid 4A by the action of spring 37 and spring washer 45A. A tension spring 42A (FIGURE 4) is connected between the pin 42 and a fixed point to eliminate backlash in the motion of the pin 42.

The wheel 30 by which the sound drum is driven in the reverse direction is continuously geared during the reverse feed to the electric motor 53 that drives the

machine. This motor is a reversible motor so that the direction in which it rotates is controlled by switch means. Clearly, it is undesirable for the motor to be started in one direction when the sound drum drive mechanism is set for the opposite direction. Therefore, a switch 46 under the control of the slide 24, is provided for preventing the motor 53 from being started in the wrong direction. A finger 47 on the slide 24 is moved to open the switch 46 when the positive drive to the sound drum is disconnected. This may be arranged to control the motor circuits in a number of ways that will be clear to those skilled in the art. For example, it may be arranged to ensure that the circuit for starting the motor in the reverse direction cannot be closed. Closure of the switch 46 may operate a relay for ensuring that the motor cannot start in the forward direction when the drive for the flywheel 11 is connected.

The motor 53 is arranged to drive the machine through a belt 74 (FIGURE 15) that embraces a pulley wheel 73 on the motor 53 and a pulley wheel 75 mounted to drive a spindle 75A (FIGURE 2). In actual fact, each of these pulley wheels has two belt surfaces of different diameters joined by a conical surface, and a belt shifting mechanism (not shown) is provided so that there is a two-speed drive in which the belt either embraces the larger diameter on one pulley and the smaller diameter on the other, or the smaller diameter on the first and the larger on the second. Either of these two speeds can be selected both for forward or reverse running.

30 The spindle 75A drives a worm 75B which meshes with a skew gear 75C for driving the sprocket 12 and with a skew gear 76 which, through a skew gear 51, drives a further skew gear 51A connected to the upper sprocket 1. Thus, when the motor is reversed, the sprockets 1 and 12 are reversed as is required.

35 The gearing for respectively driving the spools S2, S1 comprises skew gear wheels 48, 48A mounted respectively to rotate about axes 50, 55 on the crank 16A (FIGURES 8 and 12). Pulley wheels 49, 52 are fixed respectively to the gear wheels 48, 48A. The wheel 30 by which the flywheel 11 is driven is also fixed coaxially to the gear wheel 48A. When the crank 16A is in the position for reverse running, the gear wheel 48A meshes with the skew gear 51 so that a pulley wheel 54 (FIGURE 45 10) is driven, through the medium of a spring belt by the pulley wheel 52, to rotate the upper spool S1 through a friction clutch described below. When the crank 16A is in position for forward drive, the gear 48A is withdrawn from the gear 51, but the gear 48 is in mesh therewith, so that the pulley wheel 49 is rotated to drive the lower spool S2 through the belt 12B. Referring to FIGURES 10 and 11, it will be seen that the spool S1 is fixed on a spindle 55A mounted in ball bearings 56 in a casing 57 pivoted about a fixed axis 58 to a lateral protuberance on an arm 59 that is fixed to the main body of the projector so as to extend vertically upwards therefrom. Beyond the ball bearings 56, the spindle 55A carries a drum 60 encircled by a ring 61 of friction material. This lies inside a cup 62 fixed coaxially to a horizontal spindle rotatable in a bushing 63 on the arm 59 and carrying the pulley wheel 54. The axis of the spindle 55 is very slightly below the axis of the cup 62. A small finger operated lever 64 is pivoted about a fixed axis 65 on the arm 59, and a cable 66, incorporating a tension spring 67, extends between a point 68 on the lever 64 and a point 69 on the casing 57.

70 When the finger lever 64 is in the full line position of FIGURE 11, there is substantially no tension in the cable 66, so that the drum 60 and friction ring 61 are maintained in frictional engagement with the cup 62 only by the weight of the spool and of the film thereon. This is sufficient and satisfactory for the purpose of reversing the film motion, when the film is threaded over sprockets 1, 12 in the normal manner, because the speed of the film is restricted by the rate of rotation of the

sprockets and there is considerable slip between the ring 61 and the cup 62, although the tractive effort increases as the film builds up on the spool S1, thus increasing the weight and friction.

However, when it is desired to rewind the film speedily and directly between spools S2, S1, as it is the case when the film has completed its passage through the machine from spool S1 to S2, it is desirable to augment the friction due to gravity, especially when large diameter spools containing considerable lengths of film and having greater inertia are in use. For this purpose, the finger lever 64 may be moved over to the chain line position of FIG. 11. By this means, the slip between the ring 61 and the cup 62 is reduced, the tractive effect on the spool S1 is increased, and a faster rewind speed is obtained. Then, the assembly comprising the cable 66 and spring 67 is stretched due to the extension of the tension spring 67, and the corresponding increased tension causes the casing 57 to tend to turn about the axis 58, thereby increasing the frictional engagement between the ring 61 and the interior of the cup 62.

When the finger lever 64 is in the full line position (FIGURE 11), it bears against a stop 70, and when it is in the chain line position, it bears against a stop 71. To hold the lever 64 in each of these positions, a tension spring 72 is connected between a fixed point 73A and an eye 74A in the cable 66, between the spring 67 and the lever 64. When the finger lever 64 is moved in either direction between its two positions, the spring 67 is first stretched and then relaxed, so that a dead-center position is traversed.

As the drive has to be effected in opposite directions of rotation, a jockey pulley for the belt 74 is avoided and, instead, the motor 53 is fixed on a hinged platform 77 (FIGURE 13) so that the weight of the motor itself keeps the belt 74 taut in each direction of motor rotation, the hinge being at 78. Means are provided, however, for adjusting the belt tension and for this purpose an apertured extension 79 is formed on the free edge of the platform 77 and a rod 80 passes freely through the aperture and is provided at its lower end with a peripheral flange 81 which supports a helical compression spring 82 concentric with the rod 80. The portion of the extension 79 around the aperture rests on the spring 82. Therefore, the moment of the weight of the motor about the hinge 78 of the platform 77 is balanced by the moment due to the belt tension and the moment due to the spring 82. By varying the moment due to the spring 82, however, the belt tension can be varied. This is effected by raising and lowering the rod 80 so as to turn the platform slightly about its hinge 78. Raising the rod 80 takes a little tension off the belt and increases the load on the spring 82. The movement of the rod 80, therefore, has to be sufficient to accommodate the increased compression of the spring 82 as well as the slight raising of the motor 53. Lowering the rod 80 increases the tension in the belt 74 and causes the stress in the spring 82 to relax.

Means are provided also for locking the motor platform 77 against movement when it is required to transport the apparatus from place to place. For this purpose, the top of the rod 80 has pivoted thereto a two-armed lever 83, one arm 84 of which being considerably longer than the other arm 85. When the apparatus is in the operative condition, this lever is in a horizontal position shown by full lines in FIGURE 13 and rests on the top of a bushing 86 through which the rod 80 passes. This bushing 86 is screwed into a support 87, and it is by turning the bushing 86 in its support 87 that the rod 80 can be raised and lowered for adjusting the belt tension as aforesaid. The face 87A of the lever that rests on the bushing 86 is slightly convex. Strictly speaking, however, this face is constituted by two convex edges, the cross-section of the lever being U-shaped as shown in FIGURE 14 and the top of the rod 80 being pivoted

between the two limbs of the U-shaped cross-section by means of a pin 88. By turning the long arm of the lever through substantially a right angle, the end of the short arm is caused to rest on the top of the bushing, as shown in FIGURE 14 and by chain lines in FIGURE 13, the end of the short arm being flattened for this purpose. This results in the rod 80 being raised a substantial amount relatively to the bushing 86 so as to clamp the extension 79 between the lower end of the bushing 86 and a rubber cushion 89 surrounding the rod 80 within the helical spring 82 and supported by the flange 81. The cushioning effect is, of course, assisted by the spring 82 which is compressed sufficiently to bring the cushion 89 into contact with the extension 79. Moreover, the reaction due to the spring 82 and rubber cushion 89 locks the platform 77 in position.

When the apparatus is portable, a cover having deep side walls is arranged to be lowered over the apparatus until the bottom edges of the side walls make contact with the base on which the apparatus is mounted, the cover subsequently being locked in position. It is then very advantageous to arrange the lever 83, when horizontal, to obstruct the movement of the cover to its closing position, but to permit this movement when in the vertical position. This ensures that the apparatus cannot be covered and carried about before the motor has been made secure.

We claim:

1. Mechanism for feeding strip material in opposite directions between reversible rotary members and including a rotor assembly which has a substantial inertial resistance to acceleration and which comprises a drum over which the strip passes in travelling between the rotary members, said rotor assembly being rotatable freely by the strip material travelling thereover in one direction for smoothing out fluctuations in the strip movement, and means for contacting and driving the rotor assembly in the reverse direction at a speed such as to maintain tension in the strip between said drum and one of said rotary members.

2. Mechanism according to claim 1, in which the contact between said rotor assembly and said driving means is by friction.

3. Mechanism according to claim 2, in which said friction contact is provided for said rotor assembly only in the reverse of said one direction.

4. Mechanism according to claim 3, in which a driving wheel is provided, said friction driving means including a freely rotatable intermediate rotary element movable to and from a position in which it is frictionally driven by said driving wheel and frictionally drives said rotor assembly.

5. Mechanism according to claim 4, in which the diameters of the engaging surfaces of said driving wheel, intermediate rotary element and the rotor assembly are such as to provide a double step-up gearing.

6. Mechanism according to claim 4, in which a slide, a spring and a manually actuated snap action mechanism are provided, said rotary element being rotatably mounted on said slide and held in a driving position by said spring and positively moved away from said position by said manually actuated snap action mechanism.

7. Mechanism according to claim 6, in which the circumferential speed of said drum is slightly higher than the linear speed of said strip material, when said drum is being driven in the reverse direction and in which the reversely rotating drum maintains tension between said drum and said rotary member from which said strip is travelling.

8. Apparatus according to claim 7, in which an intermittent strip material feeding means is provided, said rotary member being a sprocket arranged to receive said strip material from said intermittent strip material feed-

ing means after passing over said drum, said drum being mounted between said intermittent strip feeding means and said sprocket.

9. Apparatus according to claim 8, in which a spring loaded pressure roller is provided for said drum together with a skid between said drum and said spring-loaded pressure roller, said skid being provided with spring loaded guide flanges to bear against opposite ends of said skid, additional mechanism being provided for withdrawing said flanges in their own planes to ineffective

guide positions when the direction of said strip material feed is reversed.
